TAPE RECORD PLAYER

Wayne E. Schober and Peter A. Rasmussen, Minneapolis, Minn.; said Schober assignor to Peter A. Rasmussen, doing business as Viking Tool and Die Company, Minneapolis, Minn.

Application March 29, 1957, Serial No. 45,487

Term of patent 7 years

(Cl. D26—14)

Fig. 3

Fig. 4

Fig. 1 is a view in perspective of a tape record player showing our new design;

Fig. 2 is a view in side elevation as seen from the side opposite that shown in Fig. 1;

Fig. 3 is a view in front elevation; and

Fig. 4 is a view in rear elevation.

The dominant features of our invention reside in those portions shown in full lines.

We claim:

The ornamental design for a tape record player, as shown and described.
